UNITED STATES PATENT OFFICE.

CHARLES R. BICKFORD, OF ELYRIA, OHIO, ASSIGNOR OF ONE-HALF TO
WILLIAM W. MASSEY, OF SAME PLACE.

DOOR-CHECK.

SPECIFICATION forming part of Letters Patent No. 291,466, dated January 1, 1884.

Application filed June 6, 1883. (Model.)

To all whom it may concern:

Be it known that I, CHAS. R. BICKFORD, a citizen of the United States, residing at Elyria, in the county of Lorain and State of Ohio, have invented a new and useful Door-Check, of which the following is a specification.

My invention relates to improvements in door-checks which are automatic and reversible, being actuated by means of a suitable spring. I attain these objects by means of the mechanism illustrated in the accompanying drawings, in which—

Figure 1 is a perspective view of my invention. Fig. 2 is a plan view. Fig. 3 is a broken section of the outer end of the stop, and Fig. 4 is a sectional view of Fig. 2 in the line xx .

Similar letters refer to similar parts throughout the several views.

20 The letter A is a door-stop of any suitable material and size, provided with a recess or slot of suitable width and depth cut transversely out of its upper side.

B represents a catch of suitable material and size, and of similar form to that represented in the drawings.

c is a pivotal screw or pin connecting A and B, so constructed as to allow B to freely turn.

30 D represents an escutcheon, fastened to a door, into which B may securely catch.

E is a rubber cushion, fastened in the end of A, for the purpose of breaking the jar of the door and saving injury to the same.

35 e represents a pin or projection attached rigidly to the lower side of the catch B, near the circumference of its inner end.

h is a gravity-pin, operating in and through a suitable hole in the stop A, with a suitable 40 enlarged head to prevent its falling entirely through said hole. Said pin should be long enough to project slightly below the side of said stop A.

a is a suitable spring, so constructed as to 45 operate against a projection on the catch B, and constantly exert a pressure forward to said catch B.

d is a suitable projection on the catch B, for the purpose of retaining one end of the 50 spring a.

g represents a slot or recess cut in the upper face of the stop A, for receiving the spring a.

The operation of my invention is as follows: The stop A is securely fastened to the base-board or any suitable place, and so adjusted 55

that the nose of the catch B will engage with the escutcheon D. The spring a and pin e, operating against the walls of the slot or recess g, hold the catch B in line with the edge of the door. The door, being forced back 60 against the stop A, strikes the inclined end or nose of the catch B, and forces it back until it reaches the hole in the escutcheon, when the action of the spring a forces the outer end of the catch forward into said escutcheon, and 65 retains it there until forcibly removed. The pin e is so placed that it allows the free movement of the catch B in certain prescribed distances, and by striking against the sides of the recess g prevents the catch B from being 70

forced so far back as to injure the spring a, and prevents said spring a from forcing the catch B so far forward as to be out of position for receiving the door. The gravity-pin h is set in line with the path of the pin e, and is 75 so placed that when the catch B is thrown back, as seen in the dotted lines, Fig. 2, by raising said pin h up it will be just back of the pin e. The frictional resistance of the pin e and of the pin h in its hole, caused by 80 the force of the spring a, retains it in its position, whereby it holds said catch back entirely out of use, when so desired. By pressing back on the catch B the gravity-pin h is freed from 85 its contact with the pin e, and drops back into place, allowing said catch B again free movement and operation.

What I claim as new, and desire to obtain Letters Patent of the United States for, is—

In a door-check, the rigid pin e and gravity-pin h, in combination with the spring arm or catch B, screw c, spring a, and stop A, for the purposes above set forth, and substantially as described.

CHAS. R. BICKFORD.
